UNITED STATES PATENT OFFICE.

CHARLES E. GODLEY, OF DETROIT, MICHIGAN, ASSIGNOR TO EDMUND & JONES CORPORATION, OF DETROIT, MICHIGAN, A CORPORATION OF NEW YORK.

FOCUSING DEVICE.

Application filed April 22, 1925. Serial No. 25,081.

My invention relates to devices for supporting and focusing lamp bulbs with respect to reflectors, and in general aims to provide a focusing device which will readily permit 5 adjustments to be made not only longitudinally of the axis of the reflector and in any direction transversely of the said axis, but also rotationally of this axis. Moreover, my invention aims to provide a 10 cheaply manufactured device for this purpose which can easily be attached to a reflector, which can readily be manipulated even by inexperienced persons, and which will frictionally hold the lamp socket in any 15 adjusted position when the clamping screws are slackened.

In modern automobile headlights, it is highly desirable that the reflector should spread the light to a greater extent laterally than vertically, and it is important that the position of the lamp filament should be accurately adjusted with respect to the focus of the reflector. In practice, the position of the lamp filament varies somewhat 20 in different lamp bulbs with respect to the means which interlock the base of the lamp bulb with the socket. Consequently, adjusting means are needed for shifting the lamp socket with respect to the reflector, 25 both for moving the filament of the lamp forwardly and rearwardly of the reflector and for shifting the position of the filament transversely of the axis of the reflector to make the adjustment needed in case the filament 30 is disposed at one side of the axis of the lamp base. Moreover, while standard lamp bulbs are assumed to have the two legs of each filament disposed in a plane which is in a definite position with respect 35 to the socket-engaging pins on the base of the lamp bulb, this relation is not accurately maintained in the lamp bulbs as available on the market. Consequently, such lamp bulbs will not always dispose their filaments 40 in the most effective plane for accomplishing the desired light distribution, unless the lamp bulb is suitably rotated to overcome the deviation from the proper position of the lamp filament with respect to the socket- 45 engaging pins. Hence, an adequate focusing device for use with modern headlamps should also provide means for rotationally adjusting the position of the socket which carries the lamp bulb.

My present invention provides a focusing device which will readily accomplish this rotational adjusting as well as the adjustments usually provided for moving the lamp bulb longitudinally and transversely of the reflector. It also provides an arrangement 55 for this purpose in which these several adjustments will not interfere with each other, in which a compact lamp socket forms an integral part of the focusing device, and provides a construction which may readily 60 be disassembled.

More particularly, my invention provides a focusing socket which will enable the adjustment longitudinally of the reflector to be made by manipulating a single nut, which 70 will enable both the rotational adjustment and the transverse shifting adjustments to be made by the simple shifting of a bodily movable shifting member and which will frictionally hold the parts in their adjusted 75 positions until the clamping screws are tightened. Still other and also more detailed objects of my invention will appear from the following specification and from the accompanying drawings, in which— 80

Fig. 1 is a central and longitudinal section through a focusing device embodying my invention, showing this as attached to the rear of a reflector and to a supporting bracket for the latter.

Fig. 2 is a rear view of the focusing device of Fig. 1 drawn on a reduced scale, showing the various parts of this device in their medial positions.

Fig. 3 is a section taken along the line 90 3—3 of Fig. 1 and drawn on the same scale as Fig. 2, and showing the shifting member as having been moved rotationally from the medial position of Fig. 2.

Fig. 4 is a section taken along the line 95 4—4 of Fig. 1.

Fig. 5 is a rear view of the clamping plate of the shifting member of Fig. 1.

Fig. 6 is a side elevation of the lamp socket, with a portion cut away to show the 100 extent of one of the slots which interlocks with a projection on the shifting plate which forms part of the shifting member of Fig. 1.

Fig. 7 is a reduced perspective view of the shifting plate.

Fig. 8 is a section similar to Fig. 1 showing another embodiment of my invention, namely one in which a pair of washers are

substituted for parts of the clamping plate of Figs. 1 and 5 and in which the flange on the socket is disposed between the shifting plate and an annular flange riveted to this shifting plate.

Fig. 9 is a section similar to Fig. 1, showing still another embodiment of my invention, namely one employing interengaging nub and recess formations in the two plates comprising the shifting member, and one in which the friction spring is disposed outside of the nut which effects the longitudinal adjustment of the socket.

Fig. 10 is a rear elevation of the embodiment of Fig. 9.

Fig. 11 is a rear elevation of the clamping plate of the embodiment of Fig. 9.

Fig. 12 is a perspective view of the spring used in the embodiment of Fig. 9.

In the embodiment of Figs. 1 to 7 inclusive, my focusing device includes a supporting member comprising a flat main portion 1 positioned for clamping a supporting bracket 22 against the back of a reflector 2 together with a tubular portion 3 extending through aligned apertures in the reflector and in the said bracket, this tubular portion having its forward end spun over the interior of the reflector so as to secure the supporting member rigidly to the said reflector and bracket.

Bearing against the back of the main portion 1 of the supporting member is a shifting plate 4 which desirably is provided with at least one handle 5 to facilitate its manipulation. This shifting plate 4 has a central aperture slidably fitting the tubular shell 35 of a lamp socket, while the tubular portion 3 of the supporting member has a bore of considerable larger diameter, so that the forward end of the socket can project through this tubular portion with freedom for lateral movement in all directions. The socket is here shown as including the said tubular shell 35 together with an apertured rear end 6 through which a circuit wire 7 extends, and the forward end of this wire 7 is shown as connected directly to a tack having a head 8 which forms a contact engaging the axial base terminal 9 of the lamp bulb 10.

The shell 35 of the socket is provided with the usual bayonet catch formations 26 for interlocking with lateral pins 23 on the lamp base, while an insulating washer 11 and a spring 12 are interposed between the tack head 8 and the rear end 6 of the socket so as to press this contact continuously against the base terminal 9 of the lamp bulb.

The socket shell 35 is also provided at each side with a longitudinal slot 11 which is slidably entered by a projection 12 on the shifting plate 4, thereby interlocking this plate with the socket so that the socket and lamp will be rotated whenever rotational

movement is imparted to the shifting plate. The extent of this rotation is desirably limited by providing suitable coacting means associated with this plate and with the supporting member. For this purpose I desirably utilize the shanks of two clamping screws which extend through aligned perforations 14 in both the shifting plate 4 and a clamping plate 15 disposed behind and bearing against the shifting plate, the said perforations being considerably larger than the diameters of the screw shanks which extend through them.

To allow for a longitudinal adjustment of the lamp socket with respect to the shifting plate, I do not fasten the socket direct to the latter, but employ a nut 16 threaded on the exterior of the socket and having an outwardly directed flange 17 which is interposed between portions of the shifting and clamping plates. I also employ spring means for continuously pressing this flange against one of the plates between which it is interposed and desirably arrange these spring means in such a manner that they will also take up any backlash in the threaded connection between the nut and the socket. For this combined purpose, Fig. 1 shows a compression spring 18 disposed within the nut. This spring bears forwardly against the shifting plate and rearwardly against a part of the lamp socket, the latter being desirably grooved for that purpose so as to permit the use of a relatively long spring.

The portion of the clamping plate against which the nut bears is desirably in the form of a raised ring 19 affording an annular shoulder which engages the outer edge of the nut and hence maintains the clamping plate concentric with the nut and the socket, while the engagement of the socket shell portion 35 with the perforation 24 in the clamping plate holds this latter plate concentric with the socket and nut. To prevent relative movement of the clamping and shifting plates rotationally of the axis of the socket, I provide interengaging formations on the two plates, for which purpose I may provide the shifting plate with rearwardly directed lateral flanges 25 engaging the lateral edges of the clamping plate. To permit the use of screws having relatively small heads, I dispose a washer 26 between each screw head and the clamping plate, this washer in each case being larger in diameter than the width of the perforation 14 radially of the clamping plate, and I preferably also interpose a spring washer 27 between the washer 26 and the adjacent screw head to prevent an accidental loosening of the screw.

With the focusing device thus constructed, a rotating of the nut 16 will move the socket and lamp bulb along the axis of the reflector so as to effect the desired adjustment along that axis, and the spring 18 by pressing the

flange 17 of the nut continually against the raised portion 19 of the clamping member holds the nut frictionally locked against rotation. When the clamping screws 13 are slightly relaxed, the spring 18 also operates through the said engagement of the flange 17 with the clamping plate, and through the engagement of the latter with the adjacent washer, for frictionally holding the shifting plate and the clamping plate against accidental movement. However, these two plates (which together form the shifting member of my device in this embodiment) can then be freely moved either rotationally about the axis of the reflector, or in any direction transverse of that axis within the range of movement permitted by the size of the apertures 14 with respect to the shanks of the clamping screws 13. Hence the shifting member can instantly be slid so as to move the filament of the lamp bulb into its proper focusing position, after which a tightening of the screws 13 locks the shifting member firmly in its adjusted position.

By making the shifting member of two plates interlocked against relative movement transversely of the axis of the device, and held together by the action of the clamping means, I permit my focusing device to be disassembled when desired. However, I do not wish to be limited to this arrangement, nor to the various details of construction and arrangement above described, it being obvious that many changes might be made without departing either from the spirit of my invention or from the appended claims.

For example, Fig. 8 shows another embodiment in which the flange 17 of the nut is permanently retained in operative relation to the shifting plate 4 by an annular member 28 which is secured to the shifting plate by rivets 29, and in which the washers 26 bear directly against the rear face of the shifting plate.

Fig. 9 shows an embodiment in which the handles 5 on the shifting plate are directed rearwardly, and in which the clamping plate 15^b is shortened so that the clamping screws 13^b extend through recesses open at the ends of this member. It also shows the interengaging formations on the shifting plate and the clamping plate as comprising a nub 30 on the former extending into an adjacent perforation 31 in the clamping plate, and shows a single-piece presser plate 32 as substituted for the separate washers 26 employed in the embodiments of Fig. 1 and Fig. 8.

Fig. 9 also shows another arrangement of the friction-producing means which hold the shifting member against accidental movement when the clamping screws are relaxed, namely an annular spring 33 interposed between the flange on the nut and a portion

of the clamping plate, and shows the socket as comprising a simple cylindrical shell 35^b having a contracted rear end 6^b.

With each of these embodiments, it will be noted that the various parts of the shifting member and of the clamping means comprise simple punchings in addition to the screws, and that the parts are easily assembled. It will also be noted that the manipulation of the device is exceedingly simple, as the position of the rear end of the socket with respect to the nut readily indicates the forward or rearward movement of the filament, while the transverse or rotational movement of the shifting member can be seen from the rear of the device by noting the relative position of the nut with respect to other parts.

However, while I have illustrated and described my device as used in connection with the reflector of an automobile headlamp, I do not wish to be limited to this particular employment of my invention.

I claim as my invention:

1. A focusing device comprising a supporting member having an aperture therein; a shifting member engaging the back of the supporting member and having an aperture smaller than the aperture in the supporting member; a lamp socket extending through both apertures and interlocked with the shifting member to prevent rotation of the socket, a nut swiveled upon the shifting member and threaded on the socket; and threaded means normally clamping the shifting member against the supporting member, the shifting member having an opening through which the threaded means extend and the said opening being larger than the portion of the threaded means extending through it, so as to permit a lateral shifting of the shifting member with respect to the supporting member when the threaded means are relaxed.

2. A focusing device comprising a supporting member having an aperture therein, a shifting plate engaging the supporting member and having an aperture smaller than the aperture in the supporting member, a lamp socket having a shell extending through both apertures and slidably fitting the aperture in the shifting plate, a clamping plate engaging the back of the shifting plate; a nut threaded on the socket shell and having a portion disposed between the said two plates to limit longitudinal movement of the nut with respect to the said plates; the shifting and clamping plates having two pairs of aligned openings respectively at opposite sides of the nut and having means associated with the said plates for preventing relative sliding thereof, and a pair of threaded members connecting the clamping plate with the supporting member and normally clamping the shifting plate between

the clamping plate and the supporting member, each of the said threaded members having a portion extending through one pair of the said alined openings and smaller than 5 the said openings.

3. A focusing device as per claim 2, in combination with a spring operatively interposed between the nut and one of the said plates for deterring a sliding of the said 10 plates with respect to the supporting member when the threaded means are loosened.

4. In a focusing device, a supporting member having a perforation therein, a shifting member engaging the supporting 15 member and having a relatively smaller perforation alining substantially with the perforation in the supporting member, a lamp socket extending slidably through the said smaller perforation in the shifting member, 20 a nut threaded on the socket and swiveled on the shifting member, the supporting member and the shifting member having two pairs of alined openings respectively at opposite sides of the socket shell; two 25 threaded means respectively extending through the said pairs of alined openings for normally clamping the shifting member to the supporting member, the said openings in one of the said members being larger 30 than the parts of the threaded means which extend through these perforations so as to permit movement of the shifting member transversely of the socket with respect to the supporting member when the threaded 35 means are relaxed.

5. A focusing device as per claim 4, in which the shifting member comprises an inner plate having the said smaller perforation and an outer plate having an annular

portion offset from it to afford a space between the two plates, the nut having a radial flange disposed in the said space and adapted to be clamped between the said annular portion and the inner plate.

6. A device for focusing a lamp with respect to a reflector, comprising a supporting member fast on the reflector and having an aperture, a lamp socket having a shell smaller than the aperture and extending through the same; a shifting plate supporting the socket and through which the socket shell extends slidably, the socket being interlocked with the shifting plate against relative rotational movement about the axis of the socket shell; manually releasable pressure means for clamping the shifting plate to the supporting member to prevent relative movement thereof, and spring means operatively interposed between the socket shell and the shifting plate for releasing the 50 said clamping upon a relaxing of the pressure means and for preventing lost motion in the pressure means.

7. A focusing device comprising a stationary support, a shifting member bearing 65 against the support, a nut swiveled on the shifting member, relaxable means for clamping the shifting member to the support, a socket threaded into the nut and splined to the shifting member, and means interposed 70 between the socket and the shifting member for frictionally resisting movement of the shifting member with respect to the support when the relaxable means are relaxed.
